UNITED STATES PATENT OFFICE

160,872

HOLLYWOOD BED BACK

Forrest E. Maddux, Sr., Cincinnati, Ohio, assignor to Wessel Bedding Company, Cincinnati, Ohio, a corporation of Ohio

Application October 8, 1949, Serial No. 5,386

Term of patent 7 years

(Cl. D5—2)

To all whom it may concern:

Be it known that I, Forrest E. Maddux, Sr., a citizen of the United States, residing at Cincinnati, in the county of Hamilton and State of Ohio, have invented a new, original, and ornamental Design for a Hollywood Bed Back, of which the following is a specification, reference being had to the accompanying drawing, forming a part thereof.

I claim:

The ornamental design for a Hollywood bed back, substantially as shown.

FORREST E. MADDUX, Sr.
